UNITED STATES PATENT OFFICE.

CLIFFORD L. MEYER, OF BELLEVUE BOROUGH, PENNSYLVANIA.

DESIGN FOR A CONTINUOUS-WEB MEN'S HOSE-SUPPORTER.

53,313.

Specification for Design.

Patented May 13, 1919.

Application filed June 27, 1917. Serial No. 177,402. Term of patent 14 years.

To all whom it may concern:

Be it known that I, CLIFFORD L. MEYER, a citizen of the United States, residing in the borough of Bellevue, in the county of Allegheny and State of Pennsylvania, have invented a new, original, and ornamental Design for a Continuous-Web Men's Hose-Supporter, of which the following is a specification, reference being had to the accompanying drawing, forming a part hereof.

Copies of this patent may be obtained for five cents each, by addressing the "Commissioner of Patents, Washington, D. C."

The figure is a front elevation of a continuous web men's hose supporter showing my new design.

I claim:

The ornamental design for a continuous web men's hose supporter, as shown.

CLIFFORD L. MEYER.
